UNITED STATES PATENT OFFICE.

HOWARD G. WIDMER, OF BROOKLYN, NEW YORK, ASSIGNOR TO ARKELL SAFETY BAG COMPANY, OF NEW YORK, N. Y., A CORPORATION OF NEW YORK.

DELIVERY MECHANISM FOR MACHINES FOR OPERATING ON PAPER.

1,382,583.

Specification of Letters Patent. Patented June 21, 1921.

Original application filed May 11, 1917, Serial No. 167,855. Divided and this application filed May 4, 1918. Serial No. 232,607.

To all whom it may concern:

Be it known that I, HOWARD G. WIDMER, a citizen of the United States, and a resident of the borough of Brooklyn, county of 5 Kings, and State of New York, have invented certain new and useful Improvements in Delivery Mechanism for Machines for Operating on Paper.

This invention seeks to provide convenient and efficient mechanisms for handling and delivering paper units as they come from a machine for operating upon paper. The invention is especially designed to work in connection with the machine shown and 10 described in the pending application filed by me on May 11, 1917, Serial No. 167,855, now Patent 1,362,976 granted December 21, 1920, by means of which paper tubes are formed of crinkled paper. After such tubes 15 have been formed, they are delivered from the machine by means of the mechanism herein shown and described.

The present application is a division of my earlier application above referred to.

25 In the accompanying drawings forming part of this specification, and in which like reference numerals designate corresponding parts, the invention and its various features are shown in the preferred form.

30 In the drawings,

Figure 1 is a sectional elevation of the mechanism in operative assembly.

Fig. 2 is a sectional elevation of a detail.

Fig. 3 is a plan view of Fig. 2.

35 Fig. 4 is a rear sectional view taken on the line 4—4 of Fig. 1.

Referring now to the particular structure shown in the drawings, 1 is the main frame of the machine in which are mounted 40 two rolls 2 and 3 which coöperate to complete the formation of a tube from a sheet of crinkled paper, as described in my patent above referred to. Such tube is completed by forming a seam in the two adjoining 45 margins of the sheet, such seam extending lengthwise of the tube. As the tube passes between rolls 2 and 3 it is held on roll 3 at both its leading and following margins by suitable grippers, the seam being in the following margin having been formed by the use of paste. In order that the freshly 50 pasted seam may not be injured, it is desirable to reverse the leading end of the tube before delivering it to the carrier tapes

which are to remove it from the tube forming machine. For this purpose a pan is employed to receive each tube as it comes from the rolls 2 and 3 and reverse its leading end.

4 is a tube which has just been deposited in the receiving pan 5 from roll 3. Pan 5 has a high back and a sloping bottom and is open on its sides. It is located between the rear horizontal extensions of the main frame 1 and is arranged to slide to and fro thereon. For this purpose angle brackets 6 and 7 are secured to the bottom of the pan on either side and to U-shaped slide bars 8 and 9 which extend from the front of the pan to a short distance in the rear thereof. These slide bars are held in place by guide bars 10 and 11 carried by the main frame. Bolted to the slide bars 8 and 9 are draw bars 12 and 13 extending to the rear and provided at their rear ends with rollers 14. These draw bars are provided with slots 15 immediately in front of their rollers 14 through which slots passes a shaft 16 mounted in the main frame. Fixed to each end of this shaft is a cam 17 and a friction wheel 18, the latter being provided with strips 19 of suitable friction material extending about one-third way around their peripheries. By this arrangement, as the shaft 16 rotates, the cams carried by it contact with the rollers 14 pushing them to the rear and thereby carrying the pan 5 rearward. When the cams have passed out of contact with the rollers 14, springs 20 pull the pan forward into the position shown in Fig. 1. The pan has thus a reciprocating movement from 90 and toward the roll 3. When the pan is close to the roll 3, as shown in Fig. 1, the grippers on roll 3 holding the forward end of the tube when they have reached a point just above the forward end of the pan release the tube so that this end of the tube is deposited in the receiving pan in which the forward margin of the tube comes to rest against the back of the pan. The body of the tube, after forming one or two loops, 95 overhangs the front of the pan as shown in Fig. 1. In order that the rear portion of the tube may thus overhang the pan, the latter is caused to move to the rear by mechanism already described. When about four-fifths of the tube has been deposited in the pan and the grippers on roll 3 holding the rear end of the tube have reached a point

well in front of the pan, they release their hold on the tube, thereby causing the last portion of the tube that leaves roll 3 to fall outside of the front edge of the pan and overhang it. The pan is then moved forward by its springs 20 to bring the seamed edge of the tube, which has now become the leading end between carrier tapes 21 and 22.

These carrier tapes 21 and 22 pass over 10 suitable guide pulleys and run in the same direction close together from a point where the tube is deposited between them to and around the roll 23 where they separate, the tapes 22 passing entirely around the roll 15 23 and thence down and back to the starting point, and the tapes 21 passing over the top of the roll 23 and thence around a roll 24 and back to their starting point. The tapes 22 are driven by the roll 23 on the 20 shaft 43 on which are also fixed a sprocket wheel 25 on the near end of the shaft and a second sprocket wheel (not shown) on the far end of the shaft. The tapes 21 are driven by the roll 23 and also by the roll 25 24 on the same shaft with which is fixed a sprocket wheel 26. The sprocket wheel 26 is driven from shaft 43 by a sprocket chain 44 which passes around the sprocket wheel on the far end of the shaft 43, thence partly 30 around sprocket wheel 26 and thence around an idle sprocket wheel 28. Shaft 43 is driven by a sprocket chain 27 which passes around sprocket wheel 25 and around sprocket wheel 29 on shaft 30 which is driven 35 by any suitable means.

On the shaft 16, whose movement actuates the pan 5, is fixed a sprocket wheel 31 which is driven by a sprocket chain 32 which passes around sprocket wheel 31, also part 40 way around a sprocket wheel 33 fixed on the shaft 30 and thence over two sprocket pulleys back to sprocket wheel 31.

On the rock shaft 34 is fixed an ordinary paper delivery fly having a stop bar 35 near 45 its lower end. Mounted on the rock shaft 34 is a pulley 36 to which is fixed one end of the strap 37, the other end of the strap being connected with a spring 38 attached to the main frame. Shaft 34 also carries a 50 friction pulley 41 arranged to coöperate with the friction wheel 18, for which purpose the friction strip 19 on wheel 18 is provided. When friction wheel 18 rotates, its friction surface drives pulley 41 during a 55 time that the friction strip is in contact with its pulley, thereby rocking the shaft 34 and causing the delivery fly 42 to move backward from its receiving position shown in Fig. 1 to deposit on a table the paper 60 tubes that have been delivered to it by the tapes 21 and 22. When the friction strip 19 has passed out of contact with the pulley 41, the strap 37 rocks the shaft 34 backward to return the delivery fly to its receiving position.

When the front or seamed edge of the paper tube has been delivered between the tapes 21 and 22 upon the forward movement of the pan 5, the tube is carried by these tapes over the roll 23 from which it 70 is deposited upon the delivery fly 42, the stop bar 35 preventing the tube from sliding off the fly.

While the invention is shown in what is believed to be its best form, it is to be understood that various changes in the structure and arrangement of the parts may be made without departing from the scope of the invention.

What I claim is:

1. In paper delivery mechanism, the combination of a carrier from which the paper is delivered in separate units leading end foremost; a second carrier; and a reciprocating pan adapted to receive the paper units from the first mentioned carrier and deliver them to said second carrier, said pan acting to move back from the first mentioned carrier after it has received the forward portion of a unit whereby the rear portion of the unit coming from said first mentioned carrier overhangs the front of the pan and is presented first to said second carrier.

2. In paper delivery mechanism, the combination of a roll from which the paper is delivered in separate units; carrier tapes; and a reciprocating pan adapted to receive the paper units from the roll and deliver them to said tapes, said pan acting to move 100 back from said roll after it has received the forward portion of a unit whereby the rear portion of the unit coming from said roll overhangs the front of the pan and is engaged first by said tapes.

3. In paper delivery mechanism, the combination of a roll from which the paper is delivered in separate units; carrier tapes; a reciprocating pan adapted to receive the paper units from the roll and deliver them 110 to said tapes, said pan acting to move back from said roll after it has received the forward portion of a unit whereby the rear portion of the unit coming from said roll overhangs the front of the pan and is engaged first by said tapes; cams acting to move the pan in one direction; and springs acting to move the pan in the reverse direction.

4. In paper delivery mechanism, the combination of a roll from which the paper is delivered in separate units; carrier tapes; a reciprocating pan adapted to receive the paper units from the roll and deliver them 120 to said tapes, said pan acting to move back from said roll after it has received the forward portion of a unit whereby the rear portion of the unit coming from said roll overhangs the front of the pan and is engaged first by said tapes; springs acting to 130

move the pan in one direction; a shaft provided with cams to move the pan in the reverse direction; and a rocking delivery fly actuated by said shaft.

- 5 5. In a paper tube forming machine from which the tubes are delivered with the freshly pasted seam at the rear, the combination of a reciprocative pan arranged to

receive the tubes seam edge last and deliver them seam edge first with carrier tapes to 10 receive the tubes as delivered from said pan seam edge first.

This specification signed this first day of May, A. D. 1918.

HOWARD G. WIDMER.
